UNITED STATES PATENT OFFICE.

HERMAN A. SEIFKE, OF SAN FRANCISCO, CALIFORNIA, ASSIGNOR OF TWENTY-TWO AND ONE-HALF ONE-HUNDREDTHS TO MORRIS EDELMAN, TWENTY-FIVE ONE-HUNDREDTHS TO STEVE A. BEAGLE, AND TWENTY-TWO AND ONE-HALF ONE-HUNDREDTHS TO MAX LEWIS, ALL OF SAN FRANCISCO, CALIFORNIA.

ALTERNATING-CURRENT RECTIFIER.

Application filed January 3, 1923. Serial No. 610,500.

To all whom it may concern:

Be it known that I, HERMAN A. SEIFKE, a citizen of the United States, residing in the city and county of San Francisco and State of California, have invented a new and useful Improvement in an Alternating-Current Rectifier, of which the following is a specification.

My invention relates to improvements in alternating current rectifiers and the like wherein alternating current is fed to a commutator rotated in synchronism therewith and delivered from said commutator as direct current.

15 The primary object of my invention is to provide an improved machine for rectifying alternating current.

Another object is to provide a device having improved means for regulating the voltage of the direct current output.

20 A further object is to provide an improved device wherein the alternating current supply may be conveniently controlled to direct only a desired portion of each wave length to the direct current leads.

Another object is to provide an improved device wherein the current output may be regulated independently of the direct current brushes.

30 A still further object is to provide an improved construction affording increased efficiency and durability.

I accomplish these and other objects by means of the device disclosed in the drawings forming a part of the present specification wherein like characters of reference are used to designate similar parts throughout said specification and drawings, and in which:

40 Fig. 1 is a front elevation of my improved alternating current rectifier.

Fig. 2 is an end elevation of the device shown in Fig. 1, portions of the housing members being broken away.

45 Fig. 3 is an enlarged broken sectional view of the alternating current commutator and housing showing the relation of the alternating current brush thereto.

Fig. 4 is a conventional wiring diagram of 50 my improved rectifier.

Figs. 5, 6 and 7 are diagrammatic illustrations showing the manner in which the current supply is regulated.

Referring to the drawing the numeral 1 is used to designate in general a synchronous 55 motor arranged to be connected to a source of alternating current supply not shown. The motor is provided with a starting winding 2 and a running winding 3 and is connected through a synchronizing and pole 60 controlling switch 4 and speed control switch 6 adapted to automatically bring the motor to synchronous speed to deliver current of a desired polarity, and to automatically maintain such synchronous speed, but as these 65 elements of the device are fully described in a copending application filed the 19th day of December, 1922, Serial Number 607,906, a further description is herein unnecessary.

The motor 1 is provided with a shaft 7 70 upon which a pair of commutators 8 and 9 are secured for rotation with the armature of the motor. The commutator 8, which for clearness will hereinafter be termed the direct current commutator, is provided with 75 a plurality of segments 11 corresponding to the poles of the motor, said segments being insulated from the shaft and from each other. Brushes 12 and 13 are mounted in association with the commutator segments to collect direct current therefrom in a manner hereinafter more fully described.

80 The commutator 9 hereinafter termed the alternating current commutator, is mounted in spaced relation to the commutator 8 and is provided with a like plurality of segments 14 arranged to correspond to the segments of said commutator 8 and the poles of the motor, said segments being similarly insulated from the shaft and from each other.

90 A ring 16 mounted upon the shaft 7 adjacent the commutator 8 is engaged by a brush 17, said ring being electrically connected to alternate segments 11. The brush 17 is connected to a terminal 18 arranged to receive one side of an alternating current supply line by means of a suitable connection 19.

100 The segments 11 of the commutator 8 which are not connected to the ring 16 are electrically connected to all the segments 14 of the commutator 9. The electrical connection between the commutators 8 and 9 may be effected in any suitable manner, the drawings illustrating a construction wherein rings 21 and 22 are mounted ad-

5 jacent the commutators 8 and 9 respectively and connected to segments by means of suitable conductors, connection between the rings being effected by means of a pair of 10 brushes 23 and 24 connected by a suitable conductor. This construction permits the commutator 9 to be mounted entirely apart from the commutator 8, but this construction may, of course, be modified in a great 15 number of ways without departing from the spirit of the present invention. The segments 14 of the alternating current commutator are connected through a brush 25 and conductor 26 to a terminal 27 receiving the 20 other side of the alternating current line.

From the above description it will be noted that alternate segments 11 of the direct current commutator are connected to opposite sides of the alternating current line 25 so that at any instant adjacent segments will be of opposite polarity. The segments are made of a length equivalent to 180 electrical degrees so that when the commutator is rotated at synchronous speed the 30 time required for any segment to pass a given point will be equal to the period of a half cycle. When now the motor and commutator are rotated in synchronism with the alternating current supply the polarity 35 of the segments will be reversed after each 180 electrical degrees of rotation and by positioning the brushes 12 and 13 180 electrical degrees apart at points corresponding to the neutral points it will be seen that the 40 polarity of the segments engaged by each brush will at all times be the same and the polarity at one brush will be opposite to the polarity of the other brush thereby causing the flow of current between said brushes to be at all times in the same direction and a 45 direct current obtained.

If the connection through the alternating current commutator 9 be assumed to be constant the difference in potential between the 50 brushes 12 and 13 will be equal to the difference in potential between the alternating current terminals and the current will be delivered at a voltage equal to the mean effective voltage of the alternating current supply. However, as it is highly desirable to 55 control the direct current output to obtain current at a desired voltage other than the voltage of the alternating current supply, I have arranged to control the direct current output by means of varying the alternating current feed. I accomplish this in the following manner.

The brush 25 is mounted for angular adjustment relative to the commutator 9 whereby 60 by the point of engagement between the segments 14 and the brush may be varied. This is accomplished by securing the brush upon a ring 28 pivotally movable upon a supporting member 29 and arranged to enclose the commutator 9. A spring contact

31 secured in connection with the brush 25 slidably engages an arcuate contact member 32 arranged to receive one end of the conductor 26 to maintain connection with the source of alternating current throughout the 70 range of adjustment of the brush. The brush 25 is movable through 180 electrical degrees and the extreme positions are arranged with respect to the neutral points between adjacent segments 14 of the commutator when rotated in synchronism with the alternating current to obtain a maximum degree of voltage regulation. The segments 14 are made relatively narrow and are separated by correspondingly wide insulated 75 portions. The brush 25 is made of a width substantially greater than the width of the segments 14, but less than the width of the intervening portions of insulation, so that the connection between the commutator and the alternating current supply will be momentarily broken between the time one segment 14 moves out of engagement with the brush and the succeeding segment moves 80 into engagement with the brush, and only a portion of each alternating current cycle directed through the alternating current commutator 9 to the direct current commutator segments 11 connected thereto. By 85 adjusting the brush to engage the commutator 9 at a desired point with respect to the neutral points of the commutator as determined by the positioning of the segments when the polarity is reversed by the alternating current, any desired portion of each 90 alternating current cycle may be directed through the commutator 8 and brushes 12 and 13 as direct current, and the voltage of the direct current output thereby regulated 95 between the limits hereinafter explained. The principle of this regulation is illustrated diagrammatically in Figs. 5, 6 and 7, 100 of the drawings. In Fig. 5 it is assumed that the brush 25 is positioned in such manner that at the instant the alternating current reverses a segment 14 will be just approaching the brush, and the segment will move into engagement with the brush at the same instant that the segments 11 of the 105 direct current commutator engage the brushes 12 and 13. In this position the circuit to the commutator 8 will be complete so long as the segment 14 remains in engagement with the brush 25, and the segments 115 engaged by the brushes 12 and 13 being thus connected to opposite terminals of the alternating current line a difference in potential will exist between adjacent segments and as a result current will flow through the direct current connections to said brushes 12 and 13. At the instant the segment 14 disengages the brush 25 the connection between 120 one of the segments 11 and the alternating current line will be broken and as a result 125 the difference in potential will cease to exist 130

between the brushes 12 and 13 and there will be no further flow of current. When the succeeding segment 14 engages the brush 25 the connection to the direct current commutator will be again closed, and the polarity of the segments being reversed as above described current will again be collected and flow in the same direction between the brushes 12 and 13. Thus, the first portion 10 of each alternating current impulse, which, as is well known, approximates a sine wave as illustrated, is directed to the direct current commutator and picked up by the direct current brushes, and the flow of current interrupted during the remainder of the half cycle, the portion delivered to the direct current connections being shown in heavy line while the ineffective portion is shown in light lines. In this manner it is seen that 20 the voltage of the current delivered will vary in accordance with the sine wave from zero at the start of each impulse, to the voltage at the moment the connection is broken, and the effective voltage delivered will be 25 the average of the voltage of that portion of the wave which is intercepted distributed over the period of a half cycle.

If now it is desired to increase the effective voltage, the brush 25 is moved to a position such that the segments 14 will be engaged during the periods when the voltage carried thereby is at a maximum as shown in Fig. 6. In this position, no connection to the direct current commutator is effected 35 until after the voltage of the alternating current impulse has reached a desired point, connection being maintained while the voltage is at its maximum and again broken as the voltage decreases toward the succeeding 40 neutral point. In the drawing the effective portion of each half wave length is shown in heavy lines and it will be readily seen the effective voltage of the portions intercepted will be substantially greater than that shown 45 in Fig. 5.

When it is desired to decrease the voltage, the brush is set up in a position such as that illustrated in Fig. 7 whereby only the extreme end of each impulse and the beginning 50 of the succeeding impulse is intercepted. In this manner connection is only effected when the voltage of the alternating current is at its minimum and as a result a very low mean effective voltage will be collected by the 55 brushes 12 and 13.

From the above explanation it will be readily seen that a slight adjustment of the alternating current brush will obtain a wide range of regulation with respect to the direct 60 current output without interfering in any manner with the direct current commutator and brushes. By limiting the range of adjustment the minimum voltage delivered is 65 prevented from dropping below an opposing voltage in the direct current line such as may

occur when storage batteries are being recharged, and possible damage due to such back electromotive force is thus avoided.

As above mentioned, the segments 14 are preferably made relatively short and the 70 brush 25 made long. This is done because of the fact that the tendency for sparking when the alternating current connection is broken is materially reduced and the result of such sparking made less damaging by 75 this arrangement. In order to further reduce the sparking I also provide a permanent horseshoe magnet 34 having its poles arranged upon opposite sides of the brush 25 so as to create a magnetic field across the 80 contact between the brush and the commutator. The commutator 9 being made entirely distinct from the direct current commutator may also be caused to run in oil enclosed with the ring 28 and supporting member 29 to further reduce the sparking 85 and damage caused thereby.

In order to prevent an alternating current from being directed over the direct current connections I provide an automatic cut out switch 36 arranged to normally break the direct current line until the motor and commutators have attained synchronous speed. This switch is actuated by an auxiliary circuit connected to the polarizing and synchronizing switch 4 in a manner entirely analogous to the arrangement shown and described in the copending application above referred to and a detailed description of this 90 feature of the device is therefore omitted.

While I have illustrated and described only one arrangement of my improved rectifier, the structural features are, of course, subject to wide variation without departing from the spirit of my invention. I, therefore, do not wish to restrict myself to the specific construction and arrangement disclosed but desire to avail myself of all modifications embodying the principles described and which may fall within the scope of the 100 appended claims.

Having thus described my invention what I claim as new and desire to secure by Letters Patent is:

1. In a rotary rectifier, the combination 115 with a synchronous motor and a direct current commutator associated therewith for rotation in synchronism with an alternating current supply and having a direct connection to one side of an alternating current line connected to said supply, of an independent alternating current commutator mounted for rotation therewith, said commutator having a plurality of relatively narrow segments corresponding to the poles of the motor, and electrically connected with alternate segments upon the first mentioned commutator; and a relatively long brush mounted in association with said alternating current commutator to make connection 120 125 130 135 140

thereto from the other side of the alternating current supply line during portions of each rotation to direct current during a portion of each alternating cycle to the direct current commutator, said brush being adjustable to interrupt the alternating current supply independently of the direct current commutator and its connections

2. In a rotary converter, the combination 10 with a synchronous motor and direct current commutator associated therewith for rotation in synchronism with an alternating current supply and having a direct connection to one side of an alternating current line connected to said supply, of an alternating current commutator mounted for rotation therewith, said alternating current commutator having a plurality of relatively narrow segments corresponding to the poles of the mo-

tor and electrically connected with alternate segments upon the direct current commutator; a relatively long brush mounted in association with the alternating current commutator to make connection thereto from the other side of the alternating current supply line during portions of each rotation to direct current during a portion of each alternating cycle to the direct current commutator and to interrupt the alternating current supply independently of the direct current commutator and its connections; and means for angularly adjusting said brush relative to its commutator to vary the portion of the alternating current wave length directed to the direct current commutator.

In witness whereof I hereunto set my signature.

HERMAN A. SEIFKE.
